United States Patent Office.

WILLIAM ELMER AND H. GENGBRE HUBERT, OF NEW YORK, N. Y.

Letters Patent No. 70,426, dated November 5, 1867.

IMPROVED OZONE-GENERATOR.

The Schedule referred to in these Letters Patent and making part of the same.

TO ALL WHOM IT MAY CONCERN:

Be it known that we, WILLIAM ELMER and H. G. HUBERT, both of the city, county, and State of New York, have invented certain Improvements in Ozone-Generators; and we do hereby declare that the following is a full and exact description thereof, reference being had to the accompanying drawings, forming part of this specification, in which—

Figure 1 is a sectional elevation of our ozone-generator through the line $x'x$, and

Figure 2 is a top view of the same with the cap T removed.

This invention relates to an apparatus in which ozone is generated by the reaction of certain chemical reagents, and it consists in the construction and arrangement of the parts of the apparatus, by which the chemicals are placed so as to react one on the other under the most favorable conditions.

Description.

A is a wide-mouth bottle of any ornamental or convenient shape, made of glass, china, or any inoxidizable material. B is a porous cup, made of suitable clay, and burnt so as to obtain the requisite degree of porosity. The cup B is so shaped that it enters the mouth of the vessel A, and it has a flange at top so as to rest on said mouth when placed therein. The bottom part *f* of the cup B is made dishing or concave inside, as shown in our drawings, fig. 1, and it has at or near its top part several holes *p p p*, to allow of the exit of ozone from and of the admission of air in the vessel A, even if the cup B fits the mouth of said vessel air-tight. D is a glass bottle or vial of ordinary construction, and of such dimensions that it will fit snugly in the cup B, having its rim level with the rim of the said cup B, as shown in fig. 1. E is a glass rod about the size of a goose-quill, of such a length that when placed in the bottle D, and resting on the bottom of the same, it, the rod E, will project out of the said vial D a quarter of an inch, or thereabout. T is a metal cap, deep enough to touch the mouth of the vial D and leave play between the end of the rod E and said cap T. This cap T acts as a shield to prevent an accidental blow on the end of the rod E injuring the same, or driving it through the bottom of the vial D. M is a metallic ring, of tin-foil or other soft metal, which in N is clenched or bent over the bead of the vessel A, to seal the same and hold the porous cup B fast thereto. The vessel A is filled with a porous substance, W, granulated of proper size, (about the size of coffee-beans,) asbestos, pumice-stone, baked or raw clay, &c., saturated with permanganate of potassa. Sulphuric acid is put in the vial D, the rod E is placed in said vial D, and there secured by a little plaster of Paris, forming a stopper therefor. The vial D so filled, and provided with the rod E, is now placed in the porous cup B, and there it is secured by plaster of Paris or other cement *g*, taking care to preserve therein holes P corresponding to the ones in the porous cup B. The cap T is placed over the rod E to protect it from injury. It is fastened by pasting a piece of paper over, and the porous cup being placed in the vessel A, as indicated by our drawings, the metallic ring M is placed over all, and clenched in N, finishing the ozone-generator.

Operation.

It will be observed that in our ozone-generator the two chemical agents required for producing ozone are kept apart, and are both securely packed for transportation or storage. When required for use, the cap T is removed, exposing the protruding part of the rod E. With the handle of a knife or a wooden mallet a few taps are applied on the end of the rod E, driving it in until it is flush with the balance of the apparatus. This will break the vial D, and allow the sulphuric acid contained therein to flow in the cup B. The sulphuric acid filtrating through the porous cup B, will come in contact with the porous granulated substance W, saturated with permanganate of potassa. This causes a continuous and sustained production of ozone, which will escape through the holes *p p* for a long period of time.

In specifying, the one sulphuric acid, and the other permanganate of potassa, as the two chemical reagents used in our improved ozone-generator, we do not wish to be understood as claiming the reaction of these chemicals as our invention, or as restricting ourselves to their use to the exclusion of other chemicals which may answer the same purpose. These (sulphuric acid and permanganate of potassa) are the chemicals we now employ, but we do not claim them if used for any other purposes or in any other ways than our peculiar mode of using them.

What we claim as our invention, and desire to secure by Letters Patent of the United States, is—

1. The combination and arrangement of the vessel A with the porous cup B, the one filled with the granulated porous substance W, and the other partly filled with the liquid chemical reagent Z in the manner substantially and for the purpose set forth.
2. The combination of the rod E, cement stopper e, and cap T, with the vial D and cup B, arranged so as to operate substantially in the manner specified.
3. The granulated porous substance W and the liquid chemical Z, in combination with a porous cup B, so that the reaction between the said chemical Z and substance W will take place as set forth and for the purpose specified of producing ozone.
